UNITED STATES PATENT OFFICE.

HANS POHLMANN, OF WANDSBEK, AND PAUL FRANK, OF HAMBURG, GERMANY.

CONSTRUCTION OF BUILDINGS AND PARTS OF THE SAME WHICH ARE HEAT AND COLD INSULATING.

Application filed July 22, 1920. Serial No. 398,304.

To all whom it may concern:

Be it known that we, HANS POHLMANN, a citizen of the Free State of Prussia, in the German Republic, residing at Wandsbek, in the Free State of Prussia, Germany, and PAUL FRANK, a citizen of the Free City of Hamburg, in the German Republic, residing at Hamburg, Germany, have invented Improvements in the Construction of Buildings and Parts of the Same which are Heat and Cold Insulating (for which we have filed applications in Germany August 4, 1917, August 26, 1918; Netherlands May 23, 1919); and we do hereby declare the following to be a full, clear, and exact description of the same.

This invention relates to built-up structures, such as houses, parts and other buildings of any kind and for any purpose having walls, floors and ceilings constructed in a manner to afford a very efficient insulation against heat, cold and sound.

The employment of concrete and the like is contemplated, though concrete is a comparatively good conductor of heat for the construction of columns, girders, and those supporting parts of the building, which have to carry loads, while the other parts, such as walls, are constructed from hollow bodies made of materials which possess little heat-conducting capacity. But the said columns, girders, etc., are separated from the adjacent parts of the building by air spaces. Both these air spaces and the free spaces of the aforesaid hollow bodies, however, may just as well be filled with a material of little heat-conductive properties, such as cork-meal, infusorial earth or the like.

In order that the said invention may be clearly understood and readily carried into effect, it now will be described more fully with reference to the accompanying drawings, in which:—

Figure 1 is a perspective elevation of part of a building embodying this invention, partly in section or broken away,

Figure 2 is a sectional plan view of a wall,

Figure 3 is a sectional plan view of a corner of the building,

Figure 4 is a sectional plan view of a modified construction of the wall,

Figure 5 is a sectional elevation of part of a wall and ceiling,

Figure 6 is a sectional elevation of a part of a roof structure with adjacent parts,

Figure 7 is a sectional elevation of part of a wall in a modified construction,

Figure 8 is a perspective view of part of the wall structure,

Figure 9 represents one of the reinforcing members shown in Figure 8,

Figure 10 is a sectional elevation of part of a wall in a modified construction,

Figures 11 and 12 represent each a reinforcing member adapted for use in the modification shown in Figure 10.

In Figure 1 a part of a building constructed in accordance with the invention is illustrated. All supporting parts of the same, that have to carry loads or are subject to strains are made of concrete, reinforced concrete or brick-work, or of a solid iron and wood construction. The walls, floors, ceilings and eventually the roof, however, are constructed of hollow bodies 1 in the shape of boxes, cases or similar structures. Such a hollow body represents in itself a compact unity, it being of advantage in most cases to give the body a length of the double of its width.

The hollow bodies 1 are closed on the front and back and these two sides or faces may be coated with a layer of ordinary mortar, concrete or cement-mortar either before or after they have been assembled to constitute a wall, ceiling, etc., whereas those sides that come in contact with other hollow bodies of the same kind or with insulated parts of the building are open.

To produce a ceiling or a wall, the hollow bodies are placed side by side and the joints are filled with mortar as usually done in a wall made of ordinary tiles. At the ends of the building and other places, where supporting structures must be provided, solid columns 3 and girders 4 made of concrete, reinforced concrete or brick-work, are located.

The columns 3 made of concrete are provided with reinforcements in the shape of iron bars or rods 5, or wires. The rods 5 are, if necessary, connected with each other by steady cross-wires 6 or the like. The

girder 4, lintels, door-posts, window-courses or frames and door-frames are preferably also constructed of concrete or reinforced concrete and where it is necessary, iron-
5 beams are embedded.

The construction of a building is carried on in such a way, that the bottom layer of hollow bodies is made first by placing the latter as required side by side and filling 10 the joints with mortar. Thereafter the columns or the like, if any, are built up, preferably only to the height of the adjacent layer or layers of hollow bodies 1. In some cases, however, it may be of advantage to 15 erect right away the columns or other load-carrying concrete-posts to the full of their height or up to the floor of the following upper story.

After one layer has been produced, the 20 next one above is started by placing the hollow bodies 1 again side by side and filling their joints with mortar, whereupon the column or columns are continued to be erected to the height of the second layer, 25 provided they have not been built up from the beginning to the full height of the story.

This mode of construction is continued until the walls are erected up to those points, 30 where the horizontally or otherwise arranged supporting parts, such as floor-beams or girders 4 or the like are to be placed. On top of such supporting means the wall of the next story is erected by means of hollow bodies 1 as before.

35 The connection of the columns with their adjacent parts is, according to this invention, carried out so, that a free space or clearance is formed at the places, where the hollow bodies or other parts meet the said 40 columns so that the latter are separated by an air-volume, which may act as heat-conducting bodies. This is the leading idea of the invention. The free spaces surrounding the columns may be produced by correspondingly shaping the hollow bodies 1 adjacent to the column or in lieu of such free 45 spaces insulating bodies may be arranged between the columns and the adjacent parts of the construction.

50 Figure 2 shows a horizontal section of the wall. The hollow bodies 1 comprise wooden frames covered with cardboard or similar sheets preferably connected thereto by nails. The sheets preferably consisting of water- 55 proof material, are placed parallel to each other so that air-spaces are formed by said sheets, which are separated from each other. Each hollow body comprises two parallel, right angular frames 8 made of wood, which 60 when the hollow bodies are assembled in the construction of a wall, stand vertically. These frames extend from the center of the one column to the center of the other column. The hollow body 1 further comprises 65 wooden parts 9, which preferably likewise

are shaped to form a frame and are also closed towards the outside by means of a sheet of card-board.

These parts 9 are provided with parallel, vertical grooves in which further card-board 70 sheets 10 are inserted to lie parallel to the sheets covering the frame 8 and form hollow spaces 11.

As will be seen, the columns 3 are surrounded by air-spaces 7 of the hollow bodies 75 at the outside and inside. The wall is, at the inner side and at the outer side, covered with a thick plate of concrete 12 and with a coat of mortar 2.

Figure 3 is a horizontal section through 80 the corner of a building having walls alike to that shown in Fig. 2.

In the modification shown in Fig. 4 the columns are of oblong cross-section, while the cross-section in Figs. 2 and 3 is square. 85 Besides this, only one sheet 10 is provided in the center of each hollow body 1 and the hollow body 1 is so shaped, that it surrounds the column 3 on one side with a projecting frame 6, so, that the joints are not in a 90 straight line but in staggered relation.

Fig. 5 is a sectional elevation of part of a wall. The frame 6 is here enforced by a central ledge 13. The straight line joints 95 14, between two hollow bodies 1 are filled with mortar 15 only to connect the concrete or mortar plates 12 below the mortar coat 2. They are, in order to obtain the desired insulation within their reach, subdivided by card-board strips bent over to have a certain 100 resilience.

Figure 6 is a similar sectional view of part of a roof and the adjacent parts of the building.

Below the laths 16 hollow bodies 1 are inserted whereby an excellent insulation is obtained.

Figure 7 is a sectional elevation of a wall made from hollow bodies, which are very narrow, as they only consist of wooden frames 17 with a central or medium ledge or stay 18 and two insulating card-boards 19, nailed upon the frame 17 or otherwise fastened thereto. Upon the outer card-boards 17, very thick layers of concrete or 115 mortar are placed preferably in the shape of plates 20, and free spaces 21 are provided therebetween.

As a wall so far constructed would not be at sufficient strength, reinforcing or 120 steadyng irons 22 are embedded in the joints between each two adjacent hollow bodies. The ends 23 of said irons are split and bent sideways to afford a firm grip for holding the structure in rigid connection.

125 Figure 8 illustrates part of the wall in a perspective view and Figure 9 shows a single iron or anchor 22, provided with holes 24 through which nails or bolts may be passed for fastening purposes.

In the vertical section illustrated in Fig. 10 reinforcing irons or anchors 25 of a different shape are shown, which are separately represented in Figures 11 and 12, and have 5 a single or two gripping ends 26 and 27 respectively.

In Figure 10 the hollow bodies similar to those in Figure 8 are likewise held together by irons or anchors 22. The other anchors 10 25 serve the special purpose of supporting boards 28 which co-operate with the inside faces of the wall bodies to constitute the mould for the girder 4.

In Figure 7 the frames 17 are, as already 15 mentioned, reinforced by ledges or stays 18. This is however, not always necessary. Simple square or rectangular frames without any such reinforcements may be used.

Having now described and ascertained 20 the nature of our invention and the manner in which the same is to be performed we now declare what we claim and desire to secure by Letters Patent of the United States:—

1. A building comprising walls made of 25 single superposed hollow bodies, solid supporting members made of concrete and erected at the end of said superposed bodies to form pillars or columns, and facing covers or plates made of concrete and spaced from 30 the two opposite faces of said pillars or columns to ensure a continuous air insulating space around the latter and over the said bodies.

2. A building comprising walls made of 35 single superposed hollow bodies, solid supporting pillars or columns made of concrete and erected at the end of said superposed bodies, ceilings or floors extending between said walls and said columns, girders or joists 40 made of concrete within said walls, and fac-

ing covers or plates made of concrete and spaced from the two opposite faces of said columns and from the adjacent faces of the other stated supporting members to afford a continuous insulating air space in front 45 thereof.

3. A building comprising walls made of single superposed hollow bodies, solid supporting pillars or columns made of concrete and erected at the end of said superposed bodies, facing covers or plates made of concrete and spaced from the two opposite faces of said pillars or columns, and reinforcing irons or anchors extending across through 50 the hollow bodies and the facing plates and 55 having split and bent ends to grip over the facings.

4. A building comprising walls made of single superposed hollow bodies, solid supporting pillars or columns made of concrete 60 and erected at the end of said superposed bodies, ceilings or floors extending between said walls and said columns, girders or joists made of concrete within said walls, facing plates made of concrete and spaced from 65 the two opposite faces of the said columns and from the adjacent faces of the other stated supporting members, and reinforcing irons or anchors extending across through 70 the hollow bodies and the facing plates and 75 having split and bent up ends to grip over the facing.

In testimony whereof, we have signed our names to this specification in the presence of two subscribing witnesses.

HANS POHLMANN.

PAUL FRANK.
